UNITED STATES PATENT OFFICE

LOUIS A. HOFFMAN, OF CHICAGO, ILLINOIS

ELECTRIC-LIGHT FIXTURE

Application filed September 20, 1926. Serial No. 136,398.

This invention relates to improvements in electric light fixtures, and refers more particularly to improved means of mounting a lamp socket on a support in such a manner 5 that the socket may be quickly adjusted to extend at varying angles in relation to its support.

One of the objects of the invention is to provide an improved mounting means of this 10 character comprising a ball joint which permits the lamp socket to have a universal swinging movement in all directions over a wide range.

Another object is to provide an adjustable 15 mounting means which is constructed as a part of the lamp socket itself.

A further object is to provide means for limiting the rotational adjustment of the lamp socket about its axis, so as to insure 20 against twisting off the wires leading into the socket.

In carrying out these objects I employ a ball fitting in a recess in the normally closed end of the lamp socket, the ball having an 25 attaching stem to be secured to a support, and I provide means within the lamp socket engaging said ball to hold it in place and to limit the rotational adjustment of the socket while permitting the socket to be pivoted in all directions upon the ball, so that the electric lamp in the socket may be adjusted by the user to a desired position as, for example, to accommodate the shape of the lamp shade or for other purposes.

Referring to the accompanying drawings:

Figure 1 is a fragmentary view of a floor lamp having a pair of light sockets mounted thereon by means of a preferred form of this invention.

Fig. 2 is an enlarged fragmentary elevation of the preferred form of the invention, the cap thereof being shown in section.

Fig. 3 is a plan view of the form shown in Fig. 2, a part of the cap being broken away.

Fig. 4 is an enlarged perspective of the ball member of this device.

Fig. 5 is an enlarged view of a light socket showing in longitudinal section a modification of the means for adjustably securing 50 the socket to the light fixture.

Fig. 6 is an end section of the modification taken on a line 6—6 of Fig. 5.

Although the invention is susceptible of various modifications and alternative constructions, I have shown and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

It will be readily understood that this method of mounting a light socket on a fixture may apply to any type of fixture. For the purpose of illustrating the invention, however, I have shown a floor lamp of an ordinary construction having an upright standard 5 upon the upper end of which is secured an outlet cup 6 to which a pair of 60 sockets 7 are attached.

The customary manner of securing the sockets 7 to the outlet cup 6 provides a rigid junction therebetween. I have provided what is, in effect, a ball and socket joint between the outlet cup and the light sockets, so that the sockets may have a universal swinging movement in all directions thereby permitting ready adjustment over a wide range. This joining means comprises a ball member 8 (Figs. 2, 4 and 5) preferably in the form of a short tubular member, one end of which is turned to provide a substantially spherical surface or ball 9. The other end of the ball member providing an attaching stem 10 is 85 externally screw threaded and an intermediate collar 11 separates the stem 10 from the ball 9. The outlet cup 6, from which the electric lead wires are distributed, is provided with suitable apertures to receive the stem 90 10. The collar 11 bears externally against the outlet cup 6 and cooperates with a nut 12 to secure the cup and the ball member rigidly together.

The sockets 7 are of the usual commercial 95 type in which one end is normally closed by means of a cap 13. In the present instance, this cap is provided with a central recess 14, the edges of which are turned to provide a snug bearing surface for the ball 9. 100

The recess 14 is of such size as to prevent the passage of the ball therethrough.

To provide a socket in which the ball 9 may turn universally, a clamping member such as a plate 15 having a central opening 16 corresponding to the recess 14 in the cap is secured in the cap in a suitable manner. The plate 15 may, as shown in Fig. 2, conform to the interior contour of the cap or 10 may, as shown in Figs. 5 and 6, have the form of a flat plate. The plate may be secured in the cap as by means of bolts 20 (Fig. 3), or as shown in Fig. 6, by means of a lug 17 on one edge of the plate and a screw threaded hole 18 disposed diagonally thereto. Lug 17 is arranged to enter a suitably positioned hole 19 in the cap 13 and a bolt 20^a passing through the cap into the threaded opening 18 in the plate secures the plate to the cap.

20 The arrangement of parts is such that in the assembled unit the cap 13 will contact on the surface of one hemisphere of the ball 9 while the plate 15 will bear on the surface of the other hemisphere, thus holding the ball firmly against displacement, but permitting free universal movement. By means of the bolts 20 or 20^a the frictional engagement of the plate 15 with the ball 9 may be adjustably regulated.

30 As shown in Figs. 2 and 5, a pair of lead wires 21 extend from a source of current through the ball member to suitable contacts (not shown) in the socket 7. If free axial rotation of the socket on the ball were permitted, the lead wires 21 might be twisted off. I have therefore provided a rotation stop or 35 limiting means which prevents unlimited axial rotation of the socket.

The preferred form of this limiting means is shown in Figs. 2 and 3. In this construction the edge of the recess 14 in the cap is turned outwardly to provide a shoulder 22 thereabout. The bearing surface which engages the outer hemisphere of the ball 9 is provided by means of an insert or strengthening plate 23 positioned between the cap 13 and the plate 15 and held rigidly therewith by means of the bolts 20. A stop member in the form of a semicircular bar 24, the ends of 45 which are turned inwardly as at 25, is secured between the insert plate 23 and the cap 13 in such position that it rests within the groove provided by the shoulder 22. The ball 9 is provided with a slot 26 into which the ends 50 of the bar 24 are arranged to extend. The bar 24 being held rigidly between the insert plate 23 and the cap 13 will permit a universal movement of the ball in any direction, but the ends of the bar engaging in the slot 26 55 will hold the ball against rotational movement relative to the cap. It will be apparent that it is possible to construct the cap 13 of such strength as to render the use of the insert plate 23 unnecessary. In such event the shoulder 22 would also be formed to provide

the necessary bearing surface between the cap and the ball and the bar 24 would be secured between the cap 13 and the plate 15.

A modification of the means by which the axial rotation of the ball is limited comprises 70 a rigid member such as a bar 27 fitting in the slot 26 formed in the ball 9 and extending laterally beyond the edges of the plate 15. Each end of the bar 27 is bent outwardly past the surface of the plate 15 and at certain positions of the plate relative to the ball the bent ends of the bar will contact the edges of the plate. Thus upon rotation of the socket about the ball in either direction, the bar 27 in the ball 9 will contact the edges of the plate 15 in the socket cap 13 to prevent further rotation thereof. In this modification the use of the strengthening plate 23 is unnecessary.

It will readily be seen from the foregoing 85 description that I have provided a means of mounting a light socket on a fixture which is simple and efficient, which permits an adjustable universal swinging movement of the socket on the fixture and one in which only a limited rotational movement is allowed. The mounting means is a part of the light 90 socket itself which is conducive to compactness and neatness in appearance and provides a socket which can be mounted on many varying kinds of supports.

I claim as my invention:

1. An electric light fixture comprising, in combination, a support, a lamp socket, means for attaching said socket to said support including a ball engaging in a recess in the end of said socket, said ball having a stem projecting away from said socket and attached to said support, a plate secured within said socket and engaging said ball to hold said ball in place and to hold frictionally the socket in various angles of adjustment about said ball, and means within said socket engaging said ball to limit the axial rotation of said socket about said ball.

2. An electric light fixture comprising, in combination, a supporting wall, a lamp socket, a ball positioned within one end of said socket and having a stem projecting through said supporting wall, a nut on said stem for clamping the ball to said wall, said socket being supported by said ball and permitted to move about said ball as a pivot in all directions, and means within said socket engaging said ball to limit the axial rotation 115 of the socket.

3. An electric light fixture comprising, in combination, a support, a ball mounted on and projecting from said support, a lamp socket having a portion embracing said ball to be 125 supported thereby for universal swinging movement about said ball, and means in said socket adapted to limit axial rotation of said socket on said ball, comprising a member fixed to said socket and associated with said 130

ball, said member and said ball having an engagement with each other at the limits of rotational movement of the socket.

4. An electric light fixture comprising, in combination, a support, a lamp socket, means for attaching said socket to said support including a ball engaging in a recess in the end of said socket, said ball having a stem projecting away from said socket and attached to said support, a plate secured within said socket and engaging said ball to hold said ball in place, and means to limit axial rotation of said socket on said ball, said means being located within said socket and comprising a stop member extending between said socket and said ball operable to limit the rotational movement of the socket.

5. An electric light fixture comprising, in combination, a ball, a light socket adapted to support a light and to embrace said ball, clamping means in said light socket arranged frictionally to engage said ball to permit free universal movement of said light socket relative to said ball, and means secured within said light socket adapted to limit relative axial rotation between said ball and said light socket.

6. An electric light fixture comprising, in combination, a ball, a light socket adapted to support a light and recessed to embrace said ball, a clamping plate in said light socket arranged frictionally to engage said ball to permit free universal movement of said light socket relative to said ball, and means held in said light socket by said clamping plate and engaging said ball to limit axial relative rotation between said ball and said light socket.

7. An electric light fixture comprising, in combination, a support, a ball member rigid with said support, a lamp socket having a part embracing said ball member to be supported thereby for swinging movement about said ball, and means to limit axial rotation of said socket on said ball, said means being located within said socket, comprising a plate arranged to bear against the inner hemisphere of said ball, a second plate positioned between said first mentioned plate and said socket, and means associated between one of said plates and said socket arranged to engage said ball at the limits of rotational movement in the socket.

In testimony whereof, I have hereunto affixed my signature.

LOUIS A. HOFFMAN.
